(57) **CLAIM**

The ornamental design for a housing for fan as shown and described.

DESCRIPTION

FIG. 1 is a top, front, and right side perspective view of a housing for fan showing my new design;

FIG. 2 is a top, rear, and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of area 9 circumscribed in FIG. 1.

The broken lines consisting of evenly spaced dash lines in the drawings depict portions of the housing for fan that form no part of the claimed design.

The broken lines consisting of short and long dash lines encircling the enlarged detail views are for annotative purposes that form no part of the claimed design.
